(57) **CLAIM**

The ornamental design for a dual wheel exercising device with multi-position handle, as shown and described.

DESCRIPTION

FIG. 1 is a perspective view of a dual wheel exercising device with multi-position handle showing my new design;

FIG. 2 is a front elevation view thereof;

FIG. 3 is a right elevation view thereof;

FIG. 4 is a left elevation view thereof;

FIG. 5 is a top view thereof; and,

FIG. 6 is a bottom view thereof.

1 Claim, 4 Drawing Sheets
